UNITED STATES PATENT OFFICE.

CHARLES W. SMITH, OF NORTH BALTIMORE, OHIO.

RAILROAD-TIE.

1,006,695.

Specification of Letters Patent. Patented Oct. 24, 1911.

Application filed July 3, 1911. Serial No. 636,765.

To all whom it may concern:

Be it known that I, CHARLES W. SMITH, a citizen of the United States, residing at North Baltimore, in the county of Wood and State of Ohio, have invented certain new and useful Improvements in Railroad-Ties; and I do hereby declare the following to be a full, clear, and exact description of the invention, such as will enable others skilled in the art to which it appertains to make and use the same.

This invention relates to ties for use in connection with railroad tracks; and it consists in the novel construction and combination of the parts hereinafter fully described and claimed.

In the drawings, Figure 1 is a side view of a tie constructed according to this invention. Fig. 2 is a longitudinal section 20 through the tie. Fig. 3 is a cross-section through the tie.

A is a trough-shaped bar of thin sheet metal, the bottom 2 of which rests on the ground. Two trough-shaped brackets 3 are arranged inside the bar A in a relatively inverted position, and their flat tops 4 are arranged below the tops of the flanges of the said bar. The brackets 3 are secured to the flanges of the bar A by rivets 5.

30 Buffer-blocks 6 of hard wood or other relatively soft material are arranged on top of the brackets 3, and the tops of these blocks project above the level of the tops

of the flanges of the bar A. A flat bar 7 is arranged on the buffer-blocks 6, and 10 35 are bolts which pass through holes in the blocks 6, bar 7 and through retaining washer-plates 8. These washer-plates 8 have notches 9 which engage with the flanges of the track rails. The bolts 8 are 40 inserted from below, and operate to secure the track rails to the bar 7 and the buffer-blocks. The buffer-blocks deaden the jar of a train passing over the track rails, said rails being held clear of the flanges of the 45 bar A by the buffer-blocks. This tie is manufactured at a small cost and is practically indestructible.

What I claim is:

A railroad tie, comprising a trough-shaped metallic bar, trough-shaped brackets secured to the flanges of the said bar in a relatively inverted position, buffer-blocks resting on the tops of the brackets and projecting above the flanges of the bar, a flat 50 bar arranged above the buffer-blocks, washer-plates for engaging with the track-rails, and bolts passing through holes in the said washer-plates, buffer-blocks and brackets. 55 60

In testimony whereof I have affixed my signature in the presence of two witnesses.

CHARLES W. SMITH.
